UNITED STATES PATENT OFFICE.

DONALD J. IRWIN, OF BUFFALO, MISSOURI, AND HALBERT J. STRAWN, OF ALBION, ILLINOIS.

RAIL-JOINT.

No. 844,132.

Specification of Letters Patent.

Patented Feb. 12, 1907.

Application filed September 26, 1906. Serial No. 336,261.

To all whom it may concern:

Be it known that we, DONALD J. IRWIN and HALBERT J. STRAWN, citizens of the United States, residing at Buffalo, in the county of Dallas and State of Missouri, and Albion, in the county of Edwards, State of Illinois, respectively, have invented certain new and useful Improvements in Rail-Joints, of which the following is a specification.

Our invention relates to an improvement in rail-joints, and one of the objects is to provide a simple means for rigidly securing the abutting ends of two rails together, so as to absolutely preclude the possibility of spreading or working loose or the creeping of rails.

Another object is to preserve the ends of the rails which are subjected to an excessive amount of pounding due to the heavy rolling-stock from one rail to another.

Still another object is to provide means by which the usual bolts and nuts are dispensed with in the rail-joint; and still a further object is to provide means for preventing the buckling of the rails due to expansion from heat without the necessity of cutting the rails, as is customary.

With the foregoing objects in view our invention consists in certain novel features of construction and combinations of parts, which will be hereinafter described, and pointed out in the claims.

In the accompanying drawings, Figure 1 is a plan view. Fig. 2 is a transverse section. Fig. 3 is a view of the base-plate. Fig. 4 is a view of one of the fish-plates. Fig. 5 is a perspective view of the center block. Figs. 6 and 7 are sections taken at right angles through a slightly-modified form of construction.

40 A represents a base-plate, which may be made of steel or cast-iron and in any suitable dimensions, preferably long enough to reach over two or three ties, to which it is adapted to be rigidly secured by spikes or otherwise.

45 This base-plate is provided with upturned flanges 11 at its side edges. Fish-plates 22 are made to conform substantially to the base and web of the rails 33, and they are secured upon the base-plate with the upturned flanges 11 thereof with the ends of the rails between them, and the same spikes which secure the base-plate down upon the ties may also be employed to secure the fish-plates to the base-plate, if desired, although 55 this is not necessary.

In one form of our invention we employ a removable center block 4. This is a small section of a rail and is adapted to be placed between the centers of the fish-plates, its function being, primarily, to sustain the 60 shock which the end of the rail usually bears due to the wheels rolling from one rail to another, thus taking the weight from the rail and preserving the rails in their integrity at their ends as well as throughout their length. 65 A secondary object is to provide means for preventing buckling of the track when rails expand, thus effecting a great saving in time and trouble which usually results from the cutting of rails for this purpose. When this 70 center block is used, it is provided with a slot 5 through the web just below the lower surface of the tread, and in this a clamp 6 is secured. Its ends 77 extend downwardly, the purpose of this clamp being to seat itself in 75 the notches 88 in the upper edges of the fish-plates, whereby to prevent the fish-plates spreading, also by being seated in the notches therein preventing creeping of the rails. The center block is easily removed by 80 removing one of the fish-plates, preferably the inner one, whereupon it is comparatively easy to remove the center block should occasion require its replacement or its removal altogether to relieve the buckling which results frequently from expansion of rails.

It is perfectly possible to dispense altogether with the center block and yet attain substantially the same ends, and we therefore propose as an alternative construction 90 the use of a clamp alone, such as is shown in Figs. 6 and 7, in which event the abutting ends of the rails are provided with notches 99 in the webs in position to receive the clamp, the ends of the rails being brought 95 together and the clamp, as before, straddled, the upper edges of the fish-plates being seated in the notches thereof. This construction has all the advantages of the other, except that it does not afford a rail-block such as described nor does it provide means for relieving the buckling due to expansion. In this way we have provided a very simple and at the same time rigid joint for rails, one which will not work loose. It is further- 100 more of such a nature that it prevents the spreading and creeping of rails as well.

The invention is of a character that it can readily be applied to any tracks already in existence, as well as to new constructions.

It is evident that slight changes might be resorted to in the form and arrangement of the several parts described without departure from the spirit and scope of our invention, and hence we do not wish to limit ourselves to the exact construction herein set forth; but,

Having fully described our invention, what we claim as new, and desire to secure by Letters Patent, is—

1. The combination with a flanged base-plate and rails having notched base-flanges, of fish-plates fitted to the base-plate and base and webs of the rails and having notched upper edges adapted to receive a clamp, the downwardly-turned ends of which embrace the two fish-plates, one of said fish-plates having a plurality of holes arranged in position to register with the notches in the base of the rails whether they go together or are separated a short distance, said holes adapted to receive spikes for fastening the rails in place.
2. The combination with a flanged base-plate and rails having notched base-flanges,

of fish-plates fitted to the base-plate and base and webs of the rails and having notched upper edges adapted to receive a clamp, the downwardly-turned ends of which embrace the two fish-plates, one of said fish-plates having a plurality of holes arranged in position to register with the notches in the base of the rails whether they go together or are separated a short distance, said holes adapted to receive spikes for fastening the rails in place, and a removable center block adapted to be interposed between the ends of the rails and having a slot therethrough to receive the clamp.

In testimony whereof we have signed our names to this specification in the presence of the subscribing witnesses.

DONALD J. IRWIN.
HALBERT J. STRAWN.
